(54) **SHEARING CLOTH, SHEARS FOR**

(76) Inventor: **Samuel A. Britt**

Samuel A. Bratt
Letter Patent

The Varietude referred to in this Letter Patent
and in that part of the same containing a description
in the words of this said Inventor of his
himself of his improvement in the shearing of a cloth
shearing machine

First: A revolving cylinder of three
feet or more in length three and one fourth inches in di-
ameter on which are placed four blades of steel
ground, bevelled, five eighths of an inch in width &
one fourth of an inch in thickness fastened on springs
& curved to a quarter of a circle laying flatways & con-
fined by screws to the springs resting on the cylinder, three
at each blade extending one third round the cylinder
with a set screw back of the blade thru the spring into
the cylinder for the purpose of gauging the blades —

The cylinder when put in motion, the blades come
in contact with a bed blade, laying horizontal operating
as tailors shears in its cutting. The cloth is gauged
to this bed blade as it passes the shears by an iron
rest or gauge which is $\frac{3}{4}$ of an inch thick on the
back and bent to an edge of $\frac{1}{8}$ of an inch at two inches
wide ground by screws and attached to any shearing
machine now in use
